PHOTOGRAPHIC ELEMENT CONTAINING A
PROCESSING LIQUID

William J. McCune, Jr., Cambridge, Mass., assignor to Polaroid Corporation, Cambridge, Mass., a corporation of Delaware

Application October 9, 1948, Serial No. 53,632

12 Claims. (Cl. 250—68)

1

This invention relates to photography and more particularly to novel photographic products such as film units including a plurality of photosensitive layers and a processing liquid for accomplishing a predetermined processing of each of said layers.

This invention is related to copending application Serial No. 729,579, filed February 19, 1947, now Patent No. 2,565,376, entitled "Photographic Product and Process" and application Serial No. 727,384, filed January 14, 1947, entitled "Photographic Product and Process," now abandoned and replaced by copending application Serial No. 185,642, filed September 19, 1950, now Patent No. 2,565,378, entitled "Photographic Product."

A principal object of the present invention is to provide improved film units of the above type which are simple and cheap to manufacture.

Another object of the invention is to provide such a film unit wherein a plurality of photosensitive surfaces are provided and a single liquid container is arranged so as to permit discharge of the contained liquid therefrom and spreading of this liquid across said surfaces.

Another object of the invention is to provide a product which can be formed into a film unit of the above type and wherein two photosensitive layers are carried on opposite sides of a base and a single container is associated with said two photosensitive layers to permit coverage of both said layers by a processing liquid released from said container.

Still another object of the invention is to provide a film unit of the above type, particularly adapted for dental X-ray work, wherein the processing liquid is confined in a container having an area substantially as large as the area of two photosensitive layers to be covered thereby and said film unit is arranged to permit spreading of said liquid in two separate layers across said two photosensitive layers.

Still another object of the invention is to provide an X-ray film unit of the above type wherein the liquid container is arranged to withstand extremely rough usage without rupture thereof and from which the contained liquid may be discharged and collected in a confined space, the liquid being distributed, after discharge, adjacent both sides of a double layer photosensitive assembly in position to be spread in two uniform layers across said two photosensitive layers.

These and other objects of the invention will in part be obvious and will in part appear herein-after.

The invention accordingly comprises the prod-

2

uct possessing the features, properties and the relation of components which are exemplified in the following detailed disclosure, and the scope of the application of which will be indicated in the claims.

For a fuller understanding of the nature and objects of the invention, reference should be had to the following detailed description taken in connection with the accompanying drawing wherein:

Figure 1 is a diagrammatic fragmentary sectional view of one form of film unit embodying the present invention;

Fig. 1a is a diagrammatic sectional view of the film unit of Fig. 1 during processing;

Fig. 2 is a diagrammatic fragmentary sectional view of Fig. 1 taken along line 2—2;

Fig. 3 is a diagrammatic sectional fragmentary view of another modification of the invention; and

Fig. 4 is a diagrammatic sectional fragmentary view of still another modification of the invention.

In general this invention relates to novel photographic film units. The film units preferably comprise a photosensitive assembly, including a pair of photosensitive layers carried by opposite sides of a base, and a container releasably carrying a liquid processing agent. The container is so related to the photosensitive assembly that the liquid released therefrom may be spread over both sides of the photosensitive assembly so as to simultaneously process both photosensitive layers thereof. In one preferred form of the invention the container is positioned on one side of the photosensitive assembly adjacent an edge of an image area thereof adapted to be exposed to actinic radiation. In this form of the invention the container is spaced from this edge of the image area by a small amount and the liquid in the container is confined in an area smaller than the image area to be covered by the liquid. This liquid is distributed in the container parallel to the edge of the image area adjacent which the container is positioned. The container mouth, through which the liquid is released, preferably runs parallel to this edge so that the liquid can be discharged from the mouth and spread towards the edge of the image area. Between the container mouth and the edge of the image area, there is provided a passage for the processing liquid, this passage extending from one side of the photosensitive assembly to the other side thereof. For assisting at least in the spreading of the liquid and also for supporting dry process-

ing ingredients, there are preferably provided two backing layers as a part of the film unit, there being one such backing layer on each side of the photosensitive assembly. These backing layers, or continuations thereof, are preferably coextensive in area with the image area of the photosensitive assembly and preferably overlie at least the container mouth and the liquid passage extending through the photosensitive assembly.

Where the viscosity of the processing liquid is high, which is a preferred situation, the film unit, including the photosensitive assembly and the backing layers, preferably includes a liquid barrier. This barrier, in one preferred case, is only temporary and the barrier is spaced along the film unit from the container mouth, the liquid passage being positioned between the barrier and the container mouth. A preferred type of film unit also includes a relatively permanent edge seal along the film unit, this edge seal extending along the two edges of the film unit from at least the container mouth to the temporary barrier. With such an arrangement of elements, the liquid released from the container mouth and spread towards the image area is confined in a space including one backing layer, the photosensitive assembly, the temporary barrier, and the two edge seals. Thus, as spreading of the liquid continues, the hydraulic pressure increases due to the presence of the barrier and the liquid, released on only one side of the photosensitive assembly, is forced through the liquid passage so that the processing liquid is divided between both sides of the photosensitive assembly.

Referring now to Figs. 1 and 2, there is shown one such preferred embodiment of the invention. The film unit, generally indicated at 10, comprises a photosensitive assembly 12 including a first layer 14 of a photosensitive material and a second layer 16 of a photosensitive material, these two layers being supported on opposite sides of a base 18 which is preferably transparent to the radiation used to expose the photosensitive material in layers 14 and 16. A liquid-carrying container 20, containing a predetermined quantity of a liquid processing agent 22, is preferably positioned in the film unit at one end thereof. The two photosensitive layers are preferably silver halide layers and the liquid 22 preferably comprises a viscous aqueous alkaline solution of a developer and a silver halide solvent. This container is spaced from the adjacent edge of an image area 24 of the photosensitive assembly 12 adapted to be exposed to actinic radiation, and is so positioned that a liquid-releasing mouth 26 of the container faces this adjacent edge of the image area. Between the mouth 26 and the edge of the image area there is provided a liquid passage 28 shown as a plurality of holes extending from that side of photosensitive assembly 12 which supports container 20 to the other side thereof. For assisting in spreading the processing liquid, there is provided a pair of backing layers 30, each backing layer 30 preferably including an outer actinic light-opaque stratum 32 and an inner stratum 34 which may include dry processing materials for aiding the processing of the two photosensitive layers. In this preferred form shown, the two backing layers are superposed with the container and photosensitive assembly positioned therebetween. These two backing layers are preferably sealed together at their overlapping edges so as to provide a liquid-tight seal 36 (see Fig. 2) along the edges of the film unit. The left-hand ends of the

various layers of Fig. 1 constitute a leader portion 38 for the film unit. For providing a temporary barrier to the spread of the liquid released from the container mouth 26 and spread towards the image area 24, there is provided a releasable seal 40, such as a strip of pressure-sensitive adhesive, extending transversely of the film unit.

Referring now to Fig. 1a there is shown a schematic view of the operation of the film unit of Fig. 1 during the processing thereof. For accomplishing this processing there is provided a means furnishing a pair of pressure-applying surfaces, this means being illustrated in a preferred form as a pair of pressure rolls 42. When the backing layers 30 of the film unit 10 are opaque to normal light, the photosensitive assembly 12 may be exposed to ionizing radiation, such as X-rays or radium rays, and the pressure rolls 42 need not be in a light-tight housing. These rolls may be driven by a suitable motor or a hand crank and are preferably formed of stainless steel. The rolls are preferably under a heavy spring loading to permit generation of suitable high pressures during operation. Means, such as spacers or collars, are preferably included on the rolls to predetermine the minimum spacing of the pressure-applying surfaces of the rolls, this minimum spacing being on the order of the thickness of the various layers plus the thickness desired for the two layers of spread liquid.

After exposure of the photosensitive assembly 12, such as to X-rays, the leader portion 38 of the film unit is inserted between rolls 42 and the film unit is advanced through the rolls by pulling the leader portion 38 or suitably rotating the rolls. As the container 20 enters the bite of the rolls, the liquid therein is forced from the folded edge to the sealed mouth 26 thereof, the liquid pressure generated being sufficient to rupture the seal along the mouth and to force the liquid from this mouth. Further movement of the container forces substantially all of the liquid therefrom and the liquid is spread towards the temporary barrier seal 40. When spreading of the liquid is prevented by the temporary seal 40, the hydraulic pressure therein is increased and, since the edge seals 38 prevent escape of the liquid from the film unit, the liquid is forced through the passage 28 and thus is divided between the two sides of the photosensitive assembly 12. This condition of distribution of the liquid in the film unit is shown in Fig. 1a. Further movement of the film unit through the rolls increases the hydraulic pressure on the liquid to such an extent that the temporary barrier seals 40 are ruptured and the liquid is spread down both surfaces of the photosensitive assembly. This liquid is spread in two uniform thin layers which laminate the two backing layers 30 to the two photosensitive layers included in the photosensitive assembly 12.

In a preferred form of the invention for use in X-ray work, the photosensitive assembly includes a base 18 of cellulose acetate, for example, carrying two relatively thin gelatino silver halide emulsion layers. When a negative image is the end product most desired, the gelatino silver halide emulsion preferably comprises an emulsion similar to motion picture release positive made by Eastman Kodak Co. In this case the liquid processing agent 22 preferably comprises a viscous alkaline aqueous solution of a developer, a silver halide solvent and a film-forming material.

5

One preferred liquid includes the ingredients listed in the following nonlimiting example:

Example 1

100 grams 5% water solution of sodium carboxymethyl cellulose
15 grams sodium sulfite
20 grams sodium hydroxide
12 grams hydroquinone
30 grams sodium thiosulfate

With such an emulsion and liquid composition, the backing layers 30 preferably comprise outer layers 32 of a suitable opaque material such as leader stock laminated to inner layers 34 of baryta paper, for example. The container sheet 20 is preferably formed of a paper-backed metal foil sheet coated on its inner surface with an alkali-inert plastic such as polyvinyl butyral. The metal foil sheet is folded and sealed along the mouth 26 and along the two ends, the mouth seal 26 being weaker than the end seal due to the inclusion of a strip of ethyl cellulose at the mouth seal. The barrier seal 40 preferably comprises a weak adhesive, for example, a pressure-sensitive adhesive such as a blend of unvulcanized rubber, a tack-producing resin and a softening or plasticizing agent. This pressure-sensitive adhesive is preferably coated, in a narrow strip, on layer 34.

When the liquid processing agent 22 is spread on the surfaces of the two exposed photosensitive layers 14, 16 and their respective superposed backing layers 30, the developer develops the exposed silver halide grains and the silver halide solvent forms soluble silver complexes with the unexposed silver halide grains, transporting the silver complexes from the silver halide layers to the liquid layers and the surfaces of layers 34 to fix the developing negative images.

When a pair of positive images is desired as the end product of the process, the two gelatino silver halide emulsion layers preferably comprise relatively "fast" gelatino iodobromide emulsions such as "Verichrome" or "Triple S Pan" coated on a cellulose acetate or paper base. With such a pair of emulsion layers the liquid processing agent 22 preferably includes the following ingredients:

Example 2

1860 cc. of water
107 grams medium viscosity sodium carboxymethyl cellulose
12.1 grams high viscosity sodium carboxymethyl cellulose
78.0 grams of sodium sulfite
74.6 grams of sodium hydroxide
14.5 grams of sodium thiosulfate
38.5 grams of citric acid
52.0 grams of hydroquinone
1.5 grams of chlorobenzotriazole

For use with the liquid of Example 2, and the "fast" emulsions, the inner strata 34 of the backing layers preferably comprise baryta paper treated in accordance with the following nonlimiting example:

Example 3

A sheet of single-weight baryta paper is run through a bath containing 11 grams of cadmium acetate, .37 gram of lead acetate and 11 grams of zinc nitrate per 100 cc. of water, preferably only one side of the sheet being in contact with the bath and this contact being for about 10

6

seconds. A mixture is then prepared by thoroughly mixing the following ingredients:

2700 cc. of water
278 grams of cadmium acetate
278 grams of zinc nitrate
93 grams of lead acetate
300 grams of silica aerogel
927 grams of a 3% water solution of sodium sulfide

10 This mixture is then applied to the previously prepared baryta paper by running the paper through a bath of the mixture and removing excess by means of a soft rubber roll rotating counter to the direction of travel of the sheet.

When the liquid of Example 2 is spread between the exposed "fast" emulsion layers and the baryta sheets of Example 3, negative images are developed in the emulsion layers and positive images are concurrently produced on the inner surfaces of the two baryta layers 34.

After the film unit has been processed to obtain either positive or negative images, or both, by spreading the processing liquid in accordance with the above-described procedure, the various layers are left in the form of a composite lamination for a sufficient time (1 to 2 minutes) to allow the processing reactions to go to completion. The two backing layers are then separated from the photosensitive assembly to reveal the processed images. Where a negative image is desired the backing layers may be discarded, while where positive images are desired the photosensitive assembly may be discarded.

While one preferred embodiment of the invention has been described above, numerous changes may be made therein without departing from the scope of the invention. For example, the barrier seal 40 may comprise numerous types of adhesives or mechanical bonds other than that shown and the barrier may not extend continuously across the film unit. While a continuous barrier is preferred it may equally comprise a plurality of spaced barriers which resist the spreading of liquid to a sufficient extent to force a part of the liquid through passage 28. Equally passage 28 may comprise one hole instead of several as shown. At least one backing layer 30 may be transparent to permit exposure of the photosensitive assembly to actinic light. Additionally one or both of these layers may be unsealed along the edges thereof, particularly those portions of the edges to the right of barrier seal 40 in Fig. 1, to permit movement of one or both of these layers from superposition with the photosensitive assembly during exposure thereof.

In another modification of the invention, shown in Fig. 3, the photosensitive assembly is arranged so that it may be mounted in a photographic device, such as an ordinary or X-ray camera, in a roll separate from the backing layers. In this form of the invention, the photosensitive assembly 12 comprises the two photosensitive layers 14 and 16 coated on opposite sides of base 18. 60 The photosensitive assembly 12 is connected, in a preferred form, to the container 20 by means of a pair of edge strips 44 which preferably extend from the corners of the leading edge 12a of the assembly 12 to the ends of the container 20, thus leaving an open passage 28 between the leading edge 12a and the mouth 26 of the container. The folded edge of the container is preferably similarly secured by another pair of edge strips 48 to the next preceding photosensitive assembly in the roll of assemblies and con-

ainers. A pair of backing layers 50 are shown as being formed into a composite structure with the photosensitive assembly and its associated container. For the purpose of providing a space between facing surfaces of the backing layers 50 and their adjacent photosensitive layers there are provided several spacing members 52 on each side of the leading edge 12a of the photosensitive assembly. Thus, when the liquid 22, released from container mouth 26, is spread towards leading edge 12a of assembly 12 there are two openings for the liquid to enter. Due to this arrangement, the liquid will be substantially evenly divided between the two sides of the photosensitive assembly 12. The spacing members 52 may also have the function of serving as a temporary barrier to the spread of the liquid, thus additionally assuring the equal distribution of the liquid between the two sides of the photosensitive assembly 12. The spacing members 52 are preferably secured to photosensitive assembly 12, but they may be secured to backing layers 50 in those cases where registration of the various elements is assured by the camera or by suitably associating the elements with leaders or the like. Each backing layer 50 preferably comprises an outer stratum 54 and an inner stratum 56 which are formed of materials stated as being preferable for the corresponding strata 32 and 34 of Fig. 1. The photosensitive layers 14 and 16 and the liquid 22, of the Fig. 3 modification, preferably comprise the materials mentioned in the discussion of like elements of Fig. 1.

In the use of the invention of Fig. 3, the photosensitive layers 14 and 16 are exposed to suitable radiation, such as X-rays or visible light, and the thus exposed photosensitive assembly 12 is then formed into the composite structure shown in Fig. 3 with the two backing layers on either side thereof. The composite structure so formed may then be passed between a pair of pressure-applying surfaces, such as the pressure rolls 42 of Fig. 1a. As the container passes between the rolls, the liquid is released from mouth 26 and spread towards the leading edge 12a of the photosensitive assembly. As the liquid reaches edge 12a it is divided thereby and passes into the openings provided by the spacing members 52 on each side of the assembly, these spacing members preferably acting as a sufficient barrier to the passage of the liquid to assure the substantially even distribution of this liquid on each side of assembly 12a. The spreading of the liquid is then continued until there exists a layer of the spread liquid on each side of the photosensitive assembly. The photochemical processing is then allowed to continue to completion and the various layers are separated to give positive or negative images, as the case may be.

While the modifications of the invention described above have been directed to film units and products of general photographic utility, certain features of the present invention render it particularly adaptable for dental or industrial X-ray use where the film unit is apt to be bent or otherwise deformed during positioning for exposure. A film unit so designed is illustrated at 60 in Fig. 4 where like numbers refer to like elements in the preceding figures. In this form of the invention the photosensitive assembly 12 includes the two silver halide photosensitive layers 14 and 16 coated on the base 18. Mounted on one side of the photosensitive assembly 12 is a first backing layer 62. A similar backing layer 64 is mounted on the other side of assembly 12.

Between the second backing layer 64 and an outside cover layer 66, there is provided a liquid container 68 holding a predetermined quantity of the processing liquid 22. The container comprises two walls 70 and 74 sealed together to form a liquid-releasing mouth 72. Wall 70 of container 68, preferably extends beyond the container mouth 72 and is secured to the right-hand end of the photosensitive assembly. As can be seen, the container 68 covers an area substantially as large as the area of the photosensitive assembly to be exposed to actinic radiation, and the liquid is distributed in a relatively thin layer throughout the area of the container. By means of this arrangement relatively large areas of the container walls may be pressed together under an extremely high pressure to cause a displacement of the liquid between the pressed areas of the wall without generating sufficient hydraulic pressure in the liquid to rupture the container mouth or end seals.

In a preferred form of the invention of Fig. 4 the two backing layers 62, 64 comprise baryta paper, and the photosensitive assembly 12 comprises the materials mentioned previously. The container 68 is preferably formed of a paper-backed lead foil lined with polyvinyl butyral which has a strip of ethyl cellulose along one edge to give a weaker seal at the mouth than at the ends of the container. The contained liquid 22 preferably comprises the liquid of Examples 1 or 2. The cover layer 66 preferably comprises a waterproof extensible plastic sheet, such as polyvinyl butyral or polyvinyl chloride, which contains at least a stratum which is opaque to normal visible light to form a light-tight film unit.

In the use of the invention of Fig. 4 the film unit 60 is positioned in the patient's mouth with the lower side of the film unit facing the source of X-rays or radium rays. When the exposure is made, the lead foil, forming a stratum of the container wall, acts as an antibackscatter screen so that the sharpness of the exposed latent image is maintained. The left end of the film unit is then introduced between a pair of pressure rolls, for example, and the film unit is advanced through these rolls. As the film unit advances, the liquid 22 in container 68 is forced towards the mouth 72 at the right-hand end of the film unit, enough liquid being finally moved towards mouth 72 to cause the rupturing of the mouth seal and the discharge of the liquid therefrom. When the film unit has advanced sufficiently far so that the container mouth has just passed between the rolls, the liquid will have been forced into the right-hand end of the film unit, completely filling this end, the liquid being divided between the two sides of the photosensitive assembly by means of the liquid passage 28. Advancement of the film unit is now stopped, or the rolls are separated to prevent the creation of an unduly high hydraulic pressure in the liquid. The film unit is now advanced through a second pair of pressure rolls, the direction of travel during this second passage of the film unit being opposite to the direction of travel during its first passage. Equally the same pair of pressure rolls can be used by reversing the film unit. During the second travel of the film unit the released liquid is spread from the right-hand end of the film unit between backing layer 64 and photosensitive layer 14, on one side of the photosensitive assembly, and between backing layer 62 and photosensitive layer 16, on the other side of the

photosensitive assembly. Any excess liquid being spread, when the end of the photosensitive assembly is reached, is trapped in the left-hand end of the film unit, this trapping being aided by the extensible nature of the outer layers 66 which permits the confinement of a relatively large quantity of excess liquid in this left-hand end of the film unit. After a suitable processing time the various layers are separated to reveal the developed and fixed negative images in layers 14 and 16.

Instead of having an extensible outer cover as the liquid trap, the film unit may include relatively incompressible edge spacing strips at the end of the photosensitive assembly for separating the liquid-spreading rolls and thus causing the cessation of spreading. This type of trap is particularly useful for those forms of the invention illustrated in Figs. 1 and 3. Additionally, transversely extending shoulders or suitable indicia may be provided on the film unit to either stop the film unit or to indicate to the user thereof that the film unit should not be advanced any further.

Numerous other modifications of the invention are feasible and within the scope thereof. For example, the film units of Figs. 1 or 3 may be processed in an apparatus where two pairs of pressure rolls are provided, one of these pairs of pressure rolls being positioned just in advance of the liquid-spreading pressure rolls so as to press the two backing layers against the photosensitive assembly. In such a case, no temporary barrier is necessary in the film unit since the extra pair of pressure rolls acts as the liquid barrier and forces a part of the liquid released from the container through the liquid passage. With such a modification of the invention, it may be desirable that the advance pressure rolls be separated during the further spreading of the liquid so as to simplify the creation of uniform layers of the spread liquid. This separation may be provided by including transversely extending shoulders on the edge of the film unit adjacent the image area thereof, these shoulders acting to separate the advance pair of rolls so as to make these rolls inoperative during spreading of the liquid across the exposed image area.

The modification of the invention described in connection with the discussion of Fig. 3 is particularly useful in those cases where a number of different photographic effects may be desired when using the same type of negative material and processing material for succeeding images. Thus, for example, the first image area may be processed to give a high contrast picture, while the next succeeding image area may be processed to give a low contrast image, the difference in contrast being obtained by using different types of backing layers 50 for succeeding image areas, thus giving the user of a hand-held camera, for example, wide latitude in the photographic processing reactions available.

Since certain changes may be made in the above product without departing from the scope of the invention herein involved, it is intended that all matter contained in the above description or shown in the accompanying drawing shall be interpreted as illustrative and not in a limiting sense.

What is claimed is:

1. A photographic product comprising a photosensitive assembly which includes a first silver halide photosensitive layer, a base supporting said first photosensitive layer on one side thereof

and a second silver halide photosensitive layer supported on the other side of said base, said first and second photosensitive layers having aligned predetermined areas adapted to receive image-forming actinic radiation; a liquid-carrying container having a predetermined quantity of liquid processing agent, said container having a discharge mouth adjacent an edge of said predetermined areas; means providing a passage for said liquid processing agent from said one side of said photosensitive assembly to said other side of said photosensitive assembly; a backing layer arranged to assist in spreading said liquid processing agent across said first photosensitive layer, and a second backing layer arranged to assist in spreading said liquid processing agent across the second photosensitive layer, said two backing layers being at least coextensive in area with said aligned predetermined areas, the adjacent surfaces of each photosensitive layer and its respective backing layer being separable so that liquid discharged from said container may pass between each said photosensitive layer and its respective backing layer.

2. The photographic product of claim 1 wherein said means providing a passage comprises an aperture through said photosensitive assembly.

3. The photographic product of claim 1 wherein said means providing a passage comprises a plurality of apertures through said photosensitive assembly.

4. The photographic product of claim 1 wherein said liquid processing agent comprises a viscous aqueous alkaline solution of at least one reagent from the class consisting of the silver halide developers and the silver halide solvents.

5. The photographic product of claim 1 wherein the two backing layers serve as image-receiving sheets upon which positive prints of the subject matter of latent images in said photosensitive layers are obtained.

6. A photographic product comprising a photosensitive assembly which includes a first photosensitive layer, a base supporting said first photosensitive layer on one side thereof and a second photosensitive layer supported on the other side of said base, said first and second photosensitive layers having aligned predetermined areas adapted to receive image-forming actinic radiation; a liquid-carrying container having a predetermined quantity of liquid processing agent, said container having a discharge mouth adjacent a pair of edges of said predetermined areas; means providing a passage for said liquid processing agent from said one side of said photosensitive assembly to said other side of said photosensitive assembly, said passage comprising an aperture through said photosensitive assembly; a backing layer arranged to assist in spreading said liquid processing agent across said first photosensitive layer, and a second backing layer arranged to assist in spreading said liquid processing agent across the second photosensitive layer, the respective adjacent surfaces of said photosensitive layers and said backing layers being releasably sealed along said pair of edges of said aligned predetermined areas to form a pair of liquid barriers, said respective adjacent surfaces being spaced from each other throughout the remainder of said predetermined areas whereby pressure progressively applied to consecutive portions of said backing layers causes said liquid processing agent to be emitted from said discharge mouth, thence to be spread over one photosensitive layer and to be temporarily halted

at one liquid barrier, and to be spread through said passage and over said other photosensitive layer and to be temporarily halted at the other liquid barrier, continued progressive pressure eventually rupturing said temporary barriers and thence spreading said liquid across said predetermined areas of said photosensitive layers.

7. The photographic product of claim 1 wherein said means providing a passage comprises spacer members adjacent said pair of edges of said predetermined areas, said spacer members being positioned between said photosensitive layers and their respective backing members whereby each photosensitive layer and its respective backing member are slightly separated.

8. The photographic product of claim 1 wherein said discharge mouth of said liquid-carrying container is releasably sealed and said liquid-carrying container includes flexible flat surfaces parallel to and substantially as large as one of said predetermined areas, the thickness of said container being small relative to the area of said flexible flat surfaces whereby said liquid processing agent is distributed throughout said container in a relatively thin layer so that a high compressive force applied to said container throughout a large area thereof is incapable of generating a sufficient hydraulic pressure to rupture said releasably sealed discharge mouth.

9. A photographic product comprising a photosensitive assembly which includes a first photosensitive layer, a base supporting said first photosensitive layer on one side thereof and a second photosensitive layer supported on the other side of said base, said first and second photosensitive layers having aligned predetermined areas adapted to receive image-forming actinic radiation; a liquid-carrying container having a predetermined quantity of liquid processing agent, said container having a discharge mouth adjacent an edge of said predetermined areas; means providing a passage for said liquid processing agent from said one side of said photosensitive assembly to said other side of said photosensitive assembly; a backing layer arranged to assist in spreading said liquid processing agent across said first photosensitive layer, and a second backing layer arranged to assist in spreading said liquid processing agent across the second photosensitive layer, said two backing layers being at least co-extensive in area with said aligned predetermined areas, the adjacent surfaces of each photosensitive layer and its respective backing layer being separable so that liquid discharged from said container may pass between each said photosensitive layer and its respective backing layer.

10. The photographic product of claim 1 wherein each of said backing layers comprises a first

stratum adjacent said photosensitive assembly and parallel to the plane of said photosensitive assembly, said first stratum being opaque to visual light, and a second stratum positioned between said first stratum and said photosensitive assembly, said second stratum being impregnated with dry processing materials for aiding the processing of its respective photosensitive layer.

11. The photographic product of claim 10 wherein said liquid-carrying container is positioned between said first and second strata.

12. A photographic product comprising a photosensitive assembly which includes a first photosensitive silver halide layer, a base supporting said first photosensitive layer on one side thereof and a second photosensitive silver halide layer supported on the other side of said base, said first and second photosensitive layers having aligned predetermined areas adapted to receive image-forming actinic radiation; a liquid-carrying container for a predetermined quantity of liquid processing agent, said container having a discharge mouth adjacent an edge of one of said predetermined areas; and means providing a passage for said liquid processing agent from said one side of said photosensitive assembly to said other side of said photosensitive assembly, which passage communicates with the discharge mouth of said container whereby said liquid processing agent may have access to said first and second photosensitive layers upon discharge from said liquid-carrying container.
